(57) **CLAIM**

The ornamental design for a video camera screen cover, as shown and described.

DESCRIPTION

FIG. 1 is a perspective view of a video camera screen cover illustrated in use wherein the telescoping extension has been removed;

FIG. 2 is a perspective view of the video camera screen cover illustrated in use including the telescoping extension;

FIG. 3 is a perspective view of the video camera screen cover of my design illustrated in an exploded condition;

FIG. 4 is a perspective view of the video camera screen cover of my design;

FIG. 5 is a rear elevation view thereof;

FIG. 6 is a front elevation view thereof;

FIG. 7 is a left elevation view thereof;

FIG. 8 is a right elevation view thereof;

FIG. 9 is a bottom plan view thereof; and,

FIG. 10 is top plan view thereof.

The broken lines shown represent unclaimed subject matter and form no part of the claimed design. Specifically, the camera, tripod and a fragmentary human body shown in FIGS. 1 and 2 are for environmental purpose and form no part of the claimed design.
